US0D1071227S

(12) **United States Design Patent** (10) **Patent No.:** **US D1,071,227 S**
(45) **Date of Patent:** **** Apr. 15, 2025**

(54) **POSTURE CORRECTION DEVICE**

(71) Applicant: **Deyi Sun**, Tianjin (CN)

(72) Inventor: **Deyi Sun**, Tianjin (CN)

(**) Term: **15 Years**

(21) Appl. No.: **35/514,965**

(22) Filed: **Jul. 25, 2022**

(80) **Hague Agreement Data**

Int. Filing Date: **Jul. 25, 2022**

Int. Reg. No.: **DM/222637**

Int. Reg. Date: **Jul. 25, 2022**

Int. Reg. Pub. Date: **Aug. 19, 2022**

(51) **LOC (15) Cl.** **24-02**

(52) **U.S. Cl.**

USPC **D24/190**

(57) **CLAIM**

The ornamental design for a posture correction device as shown and described.

DESCRIPTION

1. Posture correction device

1.1 : Perspective

1.2 : Perspective

1.3 : Front

1.4 : Back

1.5 : Right

1.6 : Left

1.7 : Top

1.8 : Bottom

1.9 : Enlarged

The equal-length broken lines in the drawings depict portions of the posture correction device that form no part of the claimed design.

1 Claim, 9 Drawing Sheets
